UNITED STATES PATENT OFFICE

ALFRED F. MOLIN, 617 CHAMBERS, NEW YORK, A MEMBER OF CORONA TYPEWRITER COMPANY, FOUNDED BY CORONA TYPEWRITER COMPANY OF NEW YORK.

INVENTION SPECIFICATION

1,254,826.

Specification of Letters Patent. Published Sept. 23, 1912.

Application filed January 6, 1910. Serial No. 230,021.

To all whom it may concern:

Be it known that I, Alfred F. Molin, a citizen of the Republic of Switzerland, and a resident of Grotto, in the county of Tompkins and State of New York, have invented certain new and useful Improvements in Typewriting-Machines, of which the following is a specification.

This invention relates to improvements in automatic ribbon reverse mechanism for typewriting machines.

The main object of the invention is to provide a simple and practical device for automatically rewinding the ribbon on the empty reel; and the invention consists of certain novel features of construction hereinafter described and claimed.

In the drawings, Figure 1 is a front elevation of the complete ribbon-reversing means;

Fig. 2 is a plan view thereof;

Fig. 3 a bottom view;

Fig. 4 an end elevation of the left-hand ribbon spool;

Fig. 5 a similar view of the right-hand ribbon spool;

Fig. 6 a vertical sectional view of one of the ribbon spools and its mounting;

Fig. 7 a detail plan view of one of the ribbon spool receiving cups, with the shifter switch in place therein;

Fig. 8 a detail plan view of one of the spool-receiving cups, showing the shifter switch in place;

Fig. 9 a detail plan view of the shifter switch;

Fig. 10 a front elevation of the shifter switch shown in Fig. 8;

Fig. 11 a side elevation of the shifter switch shown in Fig. 8;

Fig. 12 a detail perspective view of the spool and gear supporting sleeve;

Fig. 13 a detail perspective view of the shifter lever;

Fig. 14 a side elevation of the means for manually shifting the spool-driving gears, the gear-shifting link being shown in transverse section;

Fig. 15 and 16 front elevations of the device shown in Fig. 14, showing the parts in different positions;

Fig. 17 a view similar to Fig. 14, showing a slightly different form of device;

Figs. 18 and 19 front elevations of the device shown in Fig. 17, the parts being in different positions; and

Fig. 20 a detail perspective view of the ribbon spool sleeve.

Referring to the various parts by numbers, 1 designates the ribbon spool post which extends vertically through the ribbon spool gear sleeve 2, its lower end being screwed into a rigid support 17. The support 17, as shown in the drawings, constitutes a part of the folding arms of the well-known Corona typewriter, and the device is shown as adapted for use on that type of machine. It will, of course, be understood that the mechanism may be used on any form of typewriting machine. The ribbon spool gear 3 is formed with an angular opening and is adapted to slide up and down on the squared portion 2^a of the gear sleeve 2, in order to permit the gear to be brought into engagement with and to be disengaged from the ribbon feed worm 14. The ribbon feed worms are to be operated in any suitable manner. The gears 3 are adapted to be moved up and down on the sleeve 2 by bell-crank levers 4, said levers being pivoted at any suitable point in the frame of the machine, and provided with yokes which extend around the gears and engage between the gear and an annular 2^a flange formed on the lower end of the hub or sleeve of the gear, as clearly shown in the drawings. The upper ends of the bell-crank levers 4 are connected together by a transversely extending link 11, said link being guided and supported midway between its ends on the type guide 18. It is obvious that this link may be guided and supported in any suitable manner; and is suitably shaped to adapt it for use in the machine for which the ribbon reverse may be desired.

Rigidly mounted on each of the supports 17 is a ribbon spool receiving cup 5. As shown in the drawings, these cups are mounted on the support 17, but, of course, it will be understood that they may be supported on any rigid part of a typewriting machine frame. The gear-supporting sleeves 2 extend concentrically through these cups and the lower disks of the ribbon spools are received within the upper part of said cups. Each cup is formed with an annular upstanding flange 2^a, and with an inwardly extending horizontal ring-like portion 9^a; and with an annular spiral cam surface 9^b. By

2
tween the highest and lowest points of said spiral cam surface is formed an opening or gap 9^a, said opening being formed by cutting away a portion of the wall of the cup. In 5 the spiral cam surface at a point diametrically opposite the gap 9^a, is formed a segmental slot 9^c. At a point substantially opposite the gap 9^a is formed an outwardly extending ribbon guide 9^c, in which is formed 10 a vertical slot adapted to receive the ribbon. The flange 9^b of the cup is interrupted at a point adjacent the ribbon guide lug to form a channel through which the ribbon may extend in passing from within the cup to 15 the slot in the guide lug.

Secured to the under side of the ribbon spool receiving cup is an automatic shifter switch 8, said switch extending through the gap 9^a of the cup over the lowest point of 20 the spiral cam and into the cup, as shown in Fig. 7. The shifter switch is formed with a substantially concentric horizontal portion or trackway 8^a, which overlies the lowest part of the spiral cam 9^c of the cup 9; and 25 at its free end it is formed into a thin flexible tongue 8^b, which extends downwardly through the segmental slot in the cam surface of the cup, as shown in Fig. 7, so that the upper surface of the shifter 30 switch forms a substantially continuous annular surface at the same height or level as the highest part of the spiral cam. The spiral cam surface forms about one-half of the annular track or guideway, the other 35 half of the said track or guideway being substantially horizontal. Said substantially horizontal portion extends from the segmental slot around to the gap 9^a so that the segmental shifter switch overlies substantially the entire spiral cam surface. The 40 under side of the end of the shifter switch, adjacent the slot 9^c, is beveled downwardly to correspond with the downwardly inclined surface of the adjacent part of the annular trackway 9^c of the cup. The end of the 45 shifter-switch, adjacent the gap 9^a, is also beveled downwardly. The spool receiving cup is ring-like in general form to permit it to be placed over the ribbon spool sleeve, 50 and to permit the automatic shifter lever to operate therethrough, as will be fully hereinafter described.

Rigidly secured to the ribbon spool sleeve is a bottom disk 6, said disk being mounted 55 on the said sleeve above the squared portion 2^a. This bottom disk fits within the spool-receiving cup close to but out of contact with the shifter switch, and the annular flange 9^b of the cup, as shown clearly in Figs. 1, 2 and 5^a. This bottom disk is formed with a depending pivot lug 6^a and with an aperture 6^b, diametrically opposite the said lug. Pivotally mounted in the pivot lug 6^a is a 60 shifter lever 5, said lever being generally 65 yoke-shaped in plan view, the two arms

thereof being formed with pivot lugs, as shown clearly in Figs. 6 and 13. The shifter lever is provided with an upwardly extending ribbon-engaging arm 5^b, and with a laterally extending bearing arm 5^c, this latter arm 70 being formed with a bearing lug on its under side, which is adapted to engage and ride on the annular track of the cup and on the segmental portion of the shifter switch. The end of this bearing arm is adapted to 75 engage the flexible tongue 8^b of the shifter switch to force the same outwardly, as will be more fully hereinafter described.

The upper disk 13 of the ribbon spool carries a sleeve 7 which is adapted to be 80 forced down over the upper end of the ribbon spool supporting sleeve; and the sleeve 7 is formed with an inwardly pressed spring lug 7^a, which is adapted to engage in a slot 7^b formed in the upper end of the ribbon 85 spool supporting sleeve to insure the ribbon spool rotating with the sleeve. The end of the ribbon is secured to the spool sleeve 7 by means of a U-shaped clip which springs around and clasps the said sleeve, as indicated in Fig. 2.

Wound about the pivot of the shift lever 5 is a spring 16, one end of which bears against the under side of the spool disk 6, the other bearing upon the upper side of the 95 shift lever and tending to throw it downwardly and into engagement with the upper surface of the ribbon spool gear so that when the contact arm of the shift lever is free of the cam surface of the spool receiving cup the spring 16 will throw the said lever downwardly and carry the engaged gear 3 into mesh with its operating worm.

Mounted on a suitable rigid support is an upwardly extending bracket 12, having two 100 forwardly and upwardly extending stop arms 12^a. Pivoted on said bracket is a shift lever 10, said lever being loosely connected to the shift link 11. Connected to the upper end of the shift lever is a spring 15, the 105 other end of said spring being connected to the link 11. The link is formed with a large opening 11^a to receive the end of the spring 15, said opening being formed in the link above the pivot of the shift lever, as 110 clearly shown in Figs. 15 and 16 of the drawings. The shift lever is formed with a forwardly extending lug 10^a which extends into the opening 11^a and fits loosely therein. The object of this device is to provide means 115 for manually shifting the link 11 and thereby, through the operation of the bell-crank levers 4, reverse the direction of movement of the ribbon by disconnecting one of the ribbon spool gears from its operating 120 worm and throwing the other ribbon spool gear into mesh with its operating worm. The lever 10 is moved from one stop arm 12^a over to the other stop arm. This extends the spring 15 and when the lever has passed be- 130

yond its central vertical position the spring 16 serves to continue the movement of the link 11 in the same direction in which the lever 10 is moving. The stop arms move to limit the throw of the lever and consequently the lateral shifting movement of the link 11.

In Figs. 17, 18 and 19 the spring 16 is shown as connected to the upper end of the shift lever and to the bracket 18 below the pivotal point of the lever 10. In this arrangement of the parts the spring 16 is intended to its maximum when the lever 10 is in a vertical position, and as the lever is swung toward one or the other of the stops 15 it assists in swinging the shift link 11 and serves to snap the lever against the stops. In one arrangement of the parts the spring 16 serves to thrust the link in one or the other direction, while in the other arrangement of parts the spring tends to thrust the lever 10 and through it the link 11.

When the ribbon is unwound from one of the ribbon spools the ribbon-engaging arm of the shifter lever will be freed, and the spring 16 will throw the lever downwardly through the gap 9^a when, in the rotation of the spool, the shift lever is brought into register with said gap. The downward movement of the shift lever will bring the bearing arm 5^a to the lowermost point of the spiral cam of the spool-receiving cup. Thereafter the said contact arm will ride up said spiral cam surface until it engages the inner surface of the spring tongue 9^b of the shifter switch, pressing said switch tongue outwardly and then passing to the higher part of the annular track. As the spool continues to rotate the ribbon will be brought into engagement with the arm 5^a of the shift lever, and will hold it close to the ribbon spool sleeve 7. When the arm 5^a is held by the ribbon, the bearing arm 5^b will pass over the gap 9^a in the spool-receiving cup, and will engage the segmental supporting surface of the shifter switch. As the spool continues to rotate, the bearing arm will move on the top or upper edge of the tongue of the shifter switch and then to the high part of the annular trackway of the cup. The shifter switch, therefore, on the first one or two rotations of the ribbon spool, will prevent the bearing arm from dropping down to the lower part of the spiral cam and will maintain it in a substantially horizontal position until a sufficient number of windings of the ribbon have been placed on the spool to firmly support the switch lever and prevent it dropping to the lower part of the spiral cam surface.

When the ribbon-engaging arm of the shift lever has been freed from the ribbon and its spring 16 has thrown it downwardly to the lower part of the spiral cam surface of the cup, the engaged gear is moved downwardly and with it the corresponding bell-

crank lever 4. This movement of the bell-crank lever is transmitted to the bell-crank lever 4 of the opposite spool through the connecting link 11, thereby disengaging the opposite ribbon spool gear from its driving worm. As the link 11 is moved, the shift lever 10 is swung on its pivot, and when it is over the vertical center of its pivot the spring 16 snaps it against one of the prongs 10^a and assists the spring 16 in completing the shift of gears. The purpose of beveling the end of the shifter switch adjacent the gap 9^a is to permit the bearing arm of the shift lever to ride up to the upper surface of the shifter switch, should it drop partly through the gap 9^a when there is only one or two ribbon windings around the spool to engage the ribbon-engaging arm of the switch lever. With only one or two windings of ribbon around the spool the spring 16 would tend to force the bearing arm of the switch lever through the gap 9^a. However, as soon as a sufficient number of turns have been wound on the spool, the switch lever will be held in a substantially fixed position to avoid the reversal of the ribbon and the said lever is again freed by the complete unwinding thereof. As shown in the drawings, the ribbon-engaging arm 5^a is adapted to lie against the spool sleeve 7.

When the post 1 is in position its head 1^a is above the inwardly extending spring lug 7^a of the spool sleeve, and serves to hold the spool on the spool-supporting sleeve.

What I claim is:

1. In a typewriting machine, a ribbon spool, a spool-retaining gear connected thereto, means for rotating said gear and the connected spool, an automatically operating shift lever adapted to engage said gear and to move it downwardly into engagement with its driving means, means adapted to be engaged by the ribbon to hold said shift lever inoperative, and means connecting the gear of one ribbon spool to the gear of the other ribbon spool whereby when one gear is in mesh with its operating means the other gear will be shifted out of mesh with its driving means.

2. In a typewriting machine, a ribbon spool receiving cup formed with a spiral cam, a ribbon spool, a shift lever carried by said spool and adapted to ride on said cam when freed from the ribbon, means whereby the ribbon will hold said shift lever out of engagement with said cam, means for moving said lever into engagement with said cam when the ribbon has been unwound from said spool, and a reversing means adapted to be operated by said shift lever when freed from the ribbon.

3. In a typewriting machine, a ribbon spool, a ribbon receiving cup formed with a spiral cam, a shifter lever carried by the ribbon spool and adapted to operate on said

cam, and a shifter switch carried by said cup adapted to form a substantially horizontal trackway for the shifter lever when said lever is engaged by the ribbon.

5 4. In a typewriting machine, the combination of a pair of ribbon spools, means for rotatably supporting the spools, a pair of gears rotatable with the spools and shiftable relatively thereto, driving means for the

10 gears, and ribbon controlled means for simultaneously shifting said gears in opposite directions to operatively connect first one and then the other of said gears with its driving means.

15 5. In a typewriting machine, the combination of a pair of ribbon spools, means for rotatably supporting the spools, a pair of gears mounted on the spool supporting means to rotate with the spools and slide

20 axially relatively thereto, means for driving the gears to feed a ribbon, and means operable automatically upon exhaustion of the ribbon from either spool for shifting the gear associated with the exhausted spool

25 into operative relation with its driving means and simultaneously shifting the other gear out of operative relation with its driving means.

6. In a typewriting machine, the combination of a pair of ribbon spools, means for rotatably supporting the spools, a pair of gears rotatable with the spools and shiftable relatively thereto, driving means for the

35 gears, means connecting said gears to cause the gears to move alternately into operative relation with the driving means, a pair of gear-shifting devices rotatable with the spools normally tending to shift the gears into operative relation with the driving

40 means and each adapted to be held against gear-shifting movement by a ribbon wound on the spools until the ribbon is exhausted from its associated spool, and means associated with each gear-shifting device for

45 restoring the device associated with the spool from which the ribbon has been unwound upon reversal of the rotary movement of the spools caused by the release of said gear shifting device.

50 7. In a typewriting machine, the combination of a pair of ribbon spools, means for rotatably supporting the spools, a pair of gears rotatable with the spools and shiftable relatively thereto, driving means for the

55 gears, means connecting said gears to cause the gears to move alternately in operative relation with the driving means, a pair of gear-shifting devices rotatable with the spools normally tending to shift the gears

60 into operative relation with the driving means and each adapted to be held against gear-shifting movement by a ribbon until the ribbon is exhausted from its associated spool, means associated with each gear shifting device for restoring the device asso-

ciated with the spool from which the ribbon has been last unwound upon reversal of the rotary movement of the spools caused by the release of said gear shifting device, and automatically shiftable yieldably held means operatively connected with the gear-connecting means for holding the gears in their shifted positions.

8. Ribbon feed mechanism comprising a pair of ribbon spools, means for rotatably supporting the spools, a pair of spool driving elements rotatable with the spools and shiftable axially relatively to the spools, a pair of bell crank levers each having one arm operatively connected to shift one of said driving elements, a link connecting the other arms of the bell crank levers, means for rotating the driving elements, and a pair of pivoted spring-pressed devices rotatable with the spools adapted to engage and shift said driving elements into operative relation with said element rotating means, each of said devices having an arm adapted to be engaged by a ribbon wound on the spools to hold the device retracted until the ribbon is exhausted from the spool with which the device is associated.

9. Ribbon feed mechanism comprising a pair of ribbon spools, means for rotatably supporting the spools, a pair of spool driving elements rotatable with the spools and shiftable axially relatively to the spools, a pair of bell crank levers each having one arm operatively connected to shift one of said driving elements, a link connecting the other arms of the bell crank levers, means for rotating the driving elements, a pair of pivoted spring-pressed devices rotatable with the spools adapted to engage and shift said driving elements into operative relation with said element rotating means, each of said devices having an arm adapted to be engaged by a ribbon wound on the spools to hold the device retracted until the ribbon is exhausted from the spool with which the device is associated, and means associated with each of said devices for restoring the same against the tension of its spring upon an initial rotation of the spool from which the ribbon has been exhausted in the reverse direction.

10. Ribbon feed mechanism comprising a pair of ribbon spools, means for rotatably supporting the spools, a pair of spool driving elements rotatable with the spools and shiftable axially relatively to the spools, a pair of bell crank levers each having one arm operatively connected to shift one of said driving elements, a link connecting the other arms of the bell crank levers, means for rotating the driving elements, a pair of pivoted spring-pressed devices rotatable with the spools adapted to engage and shift said driving elements into operative relation with said element rotating means, each of said

devices having an arm adapted to be engaged by a ribbon wound on the spools to hold the device retracted until the ribbon is exhausted from the spool with which the device is associated, and an automatically shiftable yieldably held device connected with said link for holding the spool driving elements in their shifted positions.

11. Ribbon feed mechanism comprising a pair of ribbon spools, means for rotatably supporting the spools, a pair of spool driving elements rotatable with the spools and shiftable axially relatively to the spools, a pair of bell crank levers each having one arm operatively connected to shift one of said driving elements, a link connecting the other arms of the bell crank levers, means for rotating the driving elements, and a pair of pivoted spring-pressed devices rotatable with the spools adapted to engage and shift said driving elements into operative relation with said element rotating means, each of said devices having an arm adapted to be engaged by a ribbon wound on the spools to hold the device retracted until the ribbon is exhausted from the spool with which the device is associated, means associated with each of said devices for restoring the same against the tension of its spring upon an initial rotation of the spool from which the ribbon has been exhausted in the reverse direction, and an automatically shiftable yieldably held device connected with said link for holding the spool driving elements in their shifted positions.

12. Ribbon feed mechanism comprising a pair of ribbon spools, means for rotatably supporting the spools, a pair of spool driving elements rotatable with the spools and shiftable axially of the spools, means for rotating said elements, means connecting said driving elements for axial movement simultaneously in opposite directions respectively into and out of driving relation with the element rotating means, a pair of pivoted spring-pressed devices rotatable with the spools and shiftable relatively thereto to move said driving elements into driving relation with their rotating means, each of said devices having an arm adapted to be engaged by a ribbon wound on the spools to hold the device retracted until the ribbon is exhausted from the spool with which the device is associated, and a fixed cam associated with each of said devices for restoring the same upon rotation of the spool associated therewith in the reverse direction after release of said device.

device upon rotation of the spool from which the ribbon was last exhausted in the reverse direction.

13. Ribbon feed mechanism comprising a pair of ribbon spools, means for rotatably supporting the spools, a pair of spool driving elements rotatable with the spools and shiftable axially of the spools, means for rotating said elements, means connecting said driving elements for axial movement simultaneously in opposite directions respectively into and out of driving relation with the element rotating means, a pair of pivoted spring-pressed devices rotatable with the spools and shiftable relatively thereto to move said driving elements into driving relation with their rotating means, each of said devices having an arm adapted to be engaged by a ribbon wound on the spools to hold the device retracted until the ribbon is exhausted from the spool with which the device is associated, a fixed cam associated with each device for restoring said device upon rotation of the spool from which the ribbon was last exhausted in the reverse direction, and yieldable means for holding the driving elements in their shifted positions.

14. Ribbon feed mechanism comprising a pair of ribbon spools, means for rotatably supporting the spools, a pair of spool driving elements rotatable with the spools and shiftable axially relatively to the spools on said spool supporting means, a pair of bell crank levers each having one arm operatively connected to shift one of said driving elements, a link connecting the other arms of the bell crank levers, means for rotating the driving elements, a pair of pivoted spring-pressed devices rotatable with the spools adapted to engage and shift said driving elements into operative relation with said element rotating means, each of said devices having an arm adapted to be engaged by a ribbon wound on the spools to hold the device retracted until the ribbon is exhausted from the spool with which the device is associated, and a fixed cam associated with each of said spring-pressed devices for restoring the same upon rotation of the spool associated therewith in the reverse direction after release of said device.

This specification signed this 20 day of November, A. D. 1918.

ALBERT F. MOSER.
